Primary Examiner — Sandra L Morris

CLAIM

The ornamental design for a cupcake container, as shown and described.

DESCRIPTION

FIG. 1 is a front elevational view of a cupcake container showing my new design;
FIG. 2 is a rear elevational view thereof;
FIG. 3 is a left side view thereof;
FIG. 4 is a right side view thereof;
FIG. 5 is a top plan view thereof;
FIG. 6 is a first perspective view thereof; and,
FIG. 7 is a second perspective view thereof.
The oblique shade lines in the drawings indicate transparency.
